UNITED STATES PATENT OFFICE.

GEORG GRABE, OF NIKOLASSEE, NEAR BERLIN, GERMANY, ASSIGNOR TO SIEMENS & HALSKE A.-G., OF BERLIN, GERMANY, A CORPORATION OF GERMANY.

SELECTOR FOR TELEPHONE PLANTS.

1,161,126.

Specification of Letters Patent.

Patented Nov. 23, 1915.

Application filed October 15, 1913. Serial No. 795,285.

To all whom it may concern:

Be it known that I, GEORG GRABE, a German citizen, and resident of Nikolasse, near Berlin, Germany, have invented certain 5 new and useful improvements in Selectors for Telephone Plants, of which the following is a specification.

My invention in brief relates to a selector for establishing connections in telephone 10 plants by having the adjusting member retained at a desired contact by means of a locking mechanism which is mechanically brought into locking position and retained therein by a change of the magnetic condition 15 of the test electro-magnet.

The stopping and locking of automatic 20 selectors for telephone plants for establishing connections in case of certain kinds of selectors is accomplished in the manner that 25 upon the contacting of the adjusting member with the contact of a desired line, for instance a free connecting line, a counter-force is generated by the change of magnetic condition of magnets, preferably of 30 the test magnets, effecting the locking, said counter-force being in equilibrium to the driving force which is increased by the inertia of the moved masses and which brings the selector to a standstill. Such structure 35 is for instance illustrated in Figure 2 of U. S. Patent No. 975,105. In case of large selectors this force to be exerted by the magnet assumes a relatively considerable quantity, which is all the more important since 40 it must increase to its maximum during the contacting time between the adjusting member and a contact. In high-speed selectors this time will necessarily limit the speed of rotation, as the adjusting member would 45 leave the respective contact before the test magnet would be enabled to attract and retain its armature which initiates the testing and locking procedures.

According to this invention a locking of 45 the selector will be enabled at the beginning of the magnetic change of the test magnet independently of the field strength of the latter at the time attained, in that the locking member is brought mechanically, for 50 instance by the driving force for moving the selector, into the locking position, and retained in this position by said test magnet upon the contacting of the adjusting member with a contact.

55 My invention will be more fully under-

stood by reference to the accompanying drawings, which show in a diagrammatic manner a few forms of selectors according to my present invention.

Fig. 1 shows a pre-selector according to 60 my invention, Fig. 2 the connections of the same, Fig. 3 a modified form of the selector according to Fig. 1, Fig. 4 the connections of said modified form.

Referring now more particularly to the 65 several figures of the drawings I have shown a coupling disk 2 which is mounted on the axle 1 of a pre-selector provided with contact arms and a series of fixed contacts, said coupling disk forming the one part of a 70 magnetic coupling for transmitting the motion of a permanently rotating axle 3, which is provided perpendicularly to the axis of the selector. A disk 4 is mounted upon said axle 3 and is formed as a magnet pole, said 75 disk being mounted to permit swinging during rotation before the pole of the electro-magnet or coupling magnet 5, so that it will, upon excitation of the magnet 5 contact with the disk 2 and carry the same with it 80 in the direction of the arrow. Upon the axle 1 of the selector a ratchet wheel 6 is mounted having an escapement in the form of the pawl 7, said pawl being provided with a projecting part 8 forming the armature 85 of a separating relay T. This part 8 is retained in its position of rest immediately before the pole of the relay T by means of a nose 14 of a lever with several arms rotatable around a point 10, which lever operates as the armature of an electro-magnet R at one end of which a spring 11 exerts pulling force against the attracting force of the magnet of said relay R according to the drawing. The one arm 12 of the armature 90 9 extends in its position of rest into one of a number of recesses 13 provided upon a disk 15, which is mounted upon the axle of the selector. These recesses which are provided at even intervals at the periphery of the 95 disk 15 will determine the zero-positions of the selector and possess preferably a dimension extending beyond the mean-distance between two adjustments of the adjusting member, in order that the lever after catching 100 cannot again jump on account of the inertia of the locking mechanism and thereby throwing the adjusting member of the selector beyond the zero-point. By exciting 105 the coupling magnet 5 and the relay R the 110

selector will start to run whereby the pawl 7 which is released by the armature 9 will oscillate in the well known manner. The pitch of the pawl 7 and of the ratchet wheel 6 are so dimensioned that upon one oscillation of the pawl 7 the selector arm will come into the next position.

The adjustment of the pre-selector now according to the scheme shown in Fig. 2 is accomplished as follows: If the subscriber X takes the receiver off, the relay (call relay) will be excited, a circuit being formed over ground, back contact t_1 of the separating relay T, subscriber apparatus X, back contact t_2 , winding of the relay R, battery and ground. The relay R closes at r_1 the circuit of the coupling magnet 5 and the selector will start to operate. As the armature 9 releases the pawl 7 on excitation of the relay R this pawl will be enabled to freely oscillate. The excited relay R after sufficient excitation will also close its working contact r_2 , whereupon the separating relay will work in the known manner also as a test relay. If the testing arm C of the selector now meets a free line, a circuit will be closed over ground, battery, working contact r_2 , winding of the relay T, testing arm C, back contact m , relay Q and ground, the test relay T being excited up to its maximum during the motion of the testing arm C over the respective contact. At the same time by the ratchet wheel 6 the projection 8 of the pawl 7 will be moved in a direction toward the test relay T. If the selector arm now has arrived at the middle part of the desired contact, then also according to the pitch of the pawl, the armature 8 will just be moved in proximity to the pole of the relay T, in the moment of strongest magnetic action; thus locking of the selector will take place. It is not necessary that in this moment the current in the winding of the relay T have reached its full value, because the retaining pole of an armature upon contacting with the pole may be effected by a current having an essentially smaller value than if the armature had to be attracted by the pole from a greater distance. The relay T causing the testing will close in case of a sufficiently strong field its working contact t_3 , whereby a part of its resistance will be short-circuited and the connecting line locked in the known manner for other pre-selectors. Furthermore the relay T will open the back contacts t_1 and t_2 , whereby the relay R and therewith also the coupling magnet 5 will become inoperative. The deenergizing of the relays R and 5 takes an essentially longer time than would be necessary for the selector to pass the desired contact. By the retention of the projection 8 at the relay T in case of contact with the calling line the selector arm will be retained after meeting a desired contact, although the selector will still be further

driven for some time. The release of the selector, now, is accomplished by opening of the contact m in a switching apparatus which is arranged back of the pre-selector, for instance at the first group selector, whereby the relay T will become inoperative and release its armature 8. After the deenergizing of the relay T a circuit will be closed for the coupling magnet 5 over ground, battery, back contact t_4 of T, contact e , magnet 5 and ground. By this the selector again will be rotated until the arm 12 passing along the circumference of the disk 15 will fall into the next recess 13 and until the nose 14 will lock the part 8. By this also at e the circuit for the coupling magnet 5 will be opened so that now all parts have come back into their position of rest.

If the subscriber X be called from a line selector LW, the separating relay T will be excited in the known manner over the testing arm of the line selector and the line c' and disconnect the call relay R from the line by opening the back contacts t_1 and t_2 . When taking off the receiver therefore at 90 the subscriber station X no current for exciting the relay R will be caused to flow.

In the arrangement of the selector shown in Fig. 3 the pawl 7 is kept in its locking position by action of a spring 11_a, while its release will be caused by the excitation of the test relay P which will compensate by the attraction of the armature 8 provided at the pawl 7 the action of the spring so that the escapement will freely play. The selector may be advantageously operated by means of pulleys, whereby the permanently rotating cord 16 will slide over the pulley 2 in case the same is locked by the pawl 7. The escapement and the test relay are so arranged that the position of the contact arms upon the middle of a contact will correspond to the end-position of the locking member 7 which is at a distance from the pole of the relay P. The head contact h of the selector 110 will immediately be opened by a recess or groove 13 arranged in the disk 15, for one spring of the contact h during rotation of the selector axle l will slide upon the circumference of the disk 15 and thereby keep the head contact h closed as long as the selector is in a condition off from the zero-position. 115

The mode of operation of the arrangement shown in Fig. 4 for the adjustment of a selector according to Fig. 3 is as follows: If the subscriber X takes off the receiver the excited circuit of the test relay P will be closed over ground, back contact t_1' , subscriber apparatus X, back contact t_2' , back contact of the contact arm C, back contact t_3' , winding p_1 of the test magnet P, battery and ground. By the attracting force of the relay P the tensional force of the spring 11_a will be counteracted and the selector will start to rotate, the time for the field strength 130

to reach its maximum value being immaterial in this case. For explanation let it be assumed that the two first contacts of the pre-selector are otherwise occupied by having the testing strands connected to ground in the known manner. Consequently the relay P will remain excited if the arm C touches the first and second contacts, so that it will disconnect the talking contacts A and B from the subscriber line of the subscriber X by opening the back contacts p_2 and p_3 . Upon the arm C making contact with the free third contact the relay P will become inoperative, the power of the spring 11_a will come into action and press the pawl 7 into a tooth of the ratchet-wheel 6 so that the selector will be retained in position. The drop of magnetism in the relay P will begin, when the contact arm C leaves the occupied contact of the second connecting line, that is to say, before the contact arms of the selector have reached the middle of the third contact. Upon contacting with the free contact the escapement will be moved away from the pole of the magnet P. If therefore the field strength of the magnet P does not instantly disappear, it will certainly be weakened to such an extent that the action of the spring 11_a will overpower and retain the pawl 7 in its locking position. If now the armature of the relay P has fallen off, a circuit will be established over ground, battery, back contact p_4 , winding t_4 of the separating relay T', winding p_5 of the test relay P, selector arm D, resistance w of the succeeding selector, for instance the group selector, and ground. In this circuit the separating relay T' will be excited, the relay P will, however, remain inoperative, the relay T' disconnecting at t_1' and t_2' the calling circuits from the line and connecting the testing line to ground by changing over at the contact t_3' , thus locking the connecting line for other pre-selectors.

For releasing the selector at the group selector the resistance w will be short-circuited in the known manner by closing the contact m . By this the current in the circuit over the winding p_5 will be so reinforced that the relay P will now be excited over this winding. By closing the working contact p_6 of P a holding circuit will be established for both relay P and T' over ground, head contact h , working contacts t_5' and p_6 , winding t_6' of the separating relay T', winding p_1 of the test relay P, battery and ground, so that by the now established excitation of the relay P the escapement 7 will again be enabled to play freely by reason of the action of the spring 11_a being counteracted. As soon as the head contact, however, is opened by the snapping of one of its springs into a recess 13 of the disk 15, both relays will lose their excitation and all parts of the selector will now again be in the zero-position.

If the subscriber X be called from a line selector, the separating relay T' will be excited in the known manner over the testing strand c'' of the line selector, its winding t_4' , back contact p_4 , battery and ground. Thereby at t_1' and t_2' the calling circuits will be disconnected from the pre-selector.

I therefore claim as new and desire to secure by Letters Patent of the United States:—

1. A selector for telephone systems, comprising a locking device for retaining the adjusting member in a contacting position, mechanical means for bringing said locking device into locking position by the moving force for said adjusting member, and magnetic means for immediately operating said locking member when in locking position. 75

2. A selector for telephone systems, comprising a locking device for retaining the adjusting member in a contacting position, mechanical means for bringing said locking device into locking position by the moving force for said adjusting member, and magnetic means for immediately operating said locking member when in locking position and in the moment of contact between said adjusting member and the respective contact. 85

3. A selector for telephone systems, comprising an adjusting member, a locking device for retaining said adjusting member in a contacting position, mechanical means for bringing said locking member into locking position by the moving force for said adjusting member, a test magnet for immediately operating said locking member when contacting with a desired contact, and means for varying the magnetic condition of said test magnet. 95

4. A selector for telephone systems, comprising a locking device for retaining the adjusting member in contacting position, mechanical means for bringing said locking device into locking position by the moving force for said adjusting member, magnetic means for immediately operating said locking member when in locking position, means for energizing or deenergizing said magnetic means in the moment of contacting of the adjusting member with the respective contact, said mechanical and magnetic means being adapted to cause said locking device, when locking, to be in a limit-position before a magnetic pole. 115

5. A selector with a plurality of zero-positions for telephone systems, comprising a locking device for retaining the adjusting member in a contacting position, mechanical means for bringing said locking device into locking position by the moving force for said adjusting member, magnetic means for immediately operating said locking member when in locking position, members for determining the zero-positions which are of a 125

- greater dimension than the mean distance between two proximate positions of the adjusting member, for preventing the latter to be thrown beyond a zero-position by reason of the inertia of the locking mechanism.
6. A telephone selector with a plurality of zero-positions, comprising a locking device for retaining the adjusting member in a contacting position, mechanical means for bringing said locking device into locking position by the moving force for said adjusting member, magnetic means for immediately operating said locking member when in locking position, a mechanism for determining the zero-position which is greater than the mean distance between two proximate positions of the adjusting member, for preventing the latter from being thrown beyond a zero-position through the inertia of said locking device.
7. A selector for telephone systems, comprising a locking device for retaining the adjusting member in a contacting position, mechanical means for bringing said locking device into locking position by the moving force for said adjusting member, magnetic means for immediately operating said locking member when in locking position and in the moment of a desired contact of said adjusting member, a mechanism for determining a zero-position, said mechanism being larger than the mean distance between two proximate positions of the adjusting member, for preventing the latter from being thrown beyond a zero-position through the inertia of the locking mechanism.
8. A selector for telephone systems, com-

prising a locking device for retaining the adjusting member in a contacting position, mechanical means for bringing said locking device into locking position by the moving force for said adjusting member, magnetic means immediately associated with said locking member for operating the same in the moment of a desired contact made by said adjusting member, means for causing a plurality of zero-positions, said latter means being of larger dimensions than the mean-distance between two proximate positions of the adjusting member, for the purpose of preventing the latter from being thrown beyond a zero-position through the inertia of the locking mechanism.

9. A selector for telephone systems, comprising a locking device for the adjusting member, mechanical means for causing said locking device to come into locking position by the driving force of said adjusting member, a test magnet in immediate coöperation with said locking member, means for varying the magnetic condition of said test magnet, and means for producing a plurality of zero-positions, said latter means being dimensioned so as to be larger than the mean distance between two proximate positions of said adjusting member.

In witness whereof I have hereunto set my signature in the presence of two subscribing witnesses.

GEORG GRABE.
